UNITED STATES PATENT OFFICE

LEVIN GESSFORD HANDY, OF MOUNTAIN VIEW, NEW JERSEY

ATTACHMENT FOR CURTAIN RODS

Application filed December 12, 1928. Serial No. 325,423.

This invention relates to an attachment for curtain rods, and an object of the invention is to provide ornamental members which may be readily connected with a curtain rod without disarrangement of the curtain which may have been previously connected with said rod.

A further object is to provide an attachment made up of ornamental members which may be easily connected with or removed from curtain rods of the well known "Kirsch" type and which will include ornamental end members, ornamental rod covering members intermediate the end members and an ornamental centre member or members, all so designed that they may be readily attached in operative position upon rods of different lengths.

A more detailed object is to provide an attachment consisting of a plurality of separately formed members so constructed as to mate together in different adjusted positions, to the end that although said members may be manufactured each of a single given size yet they may be readily connected together for properly fitting to and forming an ornamental cover for different curtain rods of various sizes.

A further object is to provide improved means by which to fasten the members in position upon the curtain rod.

A further object is to so design the several members that they may be attached to a curtain rod regardless of whether curtains are present upon the rod or not.

A further object is to so design the members and arrange for their connection with the curtain rod that curtains may be supported either by having hems telescoping the curtain rod only or by means of rings or otherwise engaging the rod and the attachment as one.

A further object is to so design certain of the ornamental members comprising the attachment that they will serve, or appear to serve, as supporting end brackets for the other parts.

Other objects and aims of the invention, more or less specific than those referred to above, will be in part obvious and in part pointed out in the course of the following

description of the elements, combinations, arrangements of parts and applications of principles constituting the invention; and the scope of protection contemplated will be indicated in the appended claims.

55

In the accompanying drawings which are to be taken as a part of this specification, and in which I have shown merely a preferred form of embodiment of the invention:—

Fig. 1 is a front elevational view of a curtain rod having a curtain thereon and fitted with an ornamental attachment in accordance with this invention.

Fig. 2 is a top plan view of the structure seen in Fig. 1.

65

Fig. 3 is an enlarged transverse sectional view taken upon the plane of line III—III of Fig. 2.

60

Fig. 4 is a detail perspective view of one of the ornamental members employed.

70

Fig. 5 is a view similar to Fig. 4 but illustrating a modified form of the attaching means employed.

Figs. 6 and 7 are views similar to Fig. 2 but illustrating modified forms of certain of the ornamental members.

75

Fig. 8 is a detail perspective view of one of the ornamental members seen in Fig. 7.

Fig. 9 is an enlarged transverse sectional view taken upon the plane of line IX—IX of Fig. 7.

80

Fig. 10 is a front elevational view showing the use of an ornamental end bracket member.

Fig. 11 is a top plan view of the parts seen in Fig. 10, and

85

Fig. 12 is an end view of the structure seen in Figs. 10 and 11.

Referring to the drawings for describing in detail the invention as illustrated therein, the reference character L indicates a curtain rod. This is shown as being of the well known "Kirsch" type, that is as including a main straight portion 1 for extending across the width of a window or door opening, and op-

90

posite end portions 2—2 bent or curved rearwardly and provided with attaching means as 3—3 by which it may be connected with a window frame or other appropriate support as indicated at 4.

95

100

In use it is customary to hang a curtain as 5 upon this rod by threading the rod through a hem provided at the upper edge of the curtain, the opposite side edge portions of the 10 curtain continuing around the ends 2—2 of the rod as seen in Fig. 1.

The ornamental attachment with which 15 this invention is concerned consists of a pair of main cover members 6 and 7, a central ornament member 8, opposite end ornament members 9 and 10, and ornamental end bracket members 11—11.

The main cover members 6 and 7 are intended 20 to overlie the front surface of the curtain rod to cover and conceal the rod and the intervening portion of the curtain 5 if a curtain be present upon the rod. They are preferably formed of sheet metal bent so as to be concaved on their rear side to fit snugly in 25 nested relation about the rod and so as to present an appearance of increased weight and thickness as viewed from in front. Their forward faces may be suitably painted, enameled, embossed, or otherwise treated for ornamental purposes.

While the drawings herewith show two of 30 these cover members as being present it will be understood that one or any number thereof may be used as may be required to cover the curtain rod in association with which they are used. Their adjacent end portions may overlap each other, as seen in Figs. 1 to 3, or not, as preferred, or as may be required to fit them to a given length of rod. It is noted 35 that where these cover members have their end portions overlapping they nest into each other in substantially the same manner as each nests about the curtain rod.

The ornament member 8 is intended to conceal the joint between adjacent covering members and to at the same time provide means by which to fasten itself and the adjacent portion of the covering members to the curtain rod. For these purposes the member 8 40 consists of a body part 12 having suitably artistic opposite terminal extensions 13—13, the body and its terminals being of such proportions as to appropriately conceal the joint between the covering members 6 and 7. To 45 its rear surface is connected the attaching means consisting in this instance of a plurality of bendable fingers 14—14 and 15—15 arranged in pairs spaced apart longitudinally of the body adapted to straddle about the curtain rod and the covering members and to be bent against the rear surface of the curtain rod for thus clamping all of the parts firmly together. The fingers 14—15 are preferably 50 suitably pointed at their ends so that whenever necessary they may be thrust through the material of a curtain upon the rod in the same manner as disclosed in Patent No. 1,841,805, Jan. 19, 1932.

It will be understood that any desired number 55 of ornament members 8 may be attached

along the length of the rod and that although they are serviceable in concealing the joints between adjacent covering members 6—7, they may be placed at any selected points irrespective of said joints if preferred. Since the members 6—7 are shaped to nest together as described the joints are very inconspicuous in any event.

The end ornament members 9 and 10 are 60 designed to overlie the outer ends of covering members 6—7 one at each end of the curtain rod. These each consist of a main body portion 12 similar to the body portion 12 of the central ornament member 8 but have a terminal extension 13 at one end only. Attaching means is connected to the rear surface 65 consisting preferably of bendable fingers 14 and 15 for straddling about the curtain rod and the intervening portions of the covering members 6—7 in the same manner as described with regard to the member 8, said fingers being pointed at their ends for passing through the material of the curtain wherever necessary.

In the illustration Fig. 4 a rear view is 70 presented showing one of these end ornament members, and including dotted line representation of an artistic terminal extension at its opposite end, it being understood that the body 12 is substantially the same in either 75 instance and has a single artistic extension 13 when intended for use as an end member 9 or 10 but having double artistic extensions 13 when intended for use as a central member 8. This view also suggests that if desired the pairs of bendable fingers 14—14 and 15—15 may be formed each pair from a single 80 length of wire soldered or otherwise connected with the body 12 at its mid-portion so that its opposite ends are bendable into any 85 positions for facilitating their engagement about the curtain rod and the intervening curtain and covering members.

In the modification Fig. 5 it is suggested 90 that the body portion 12 may be provided with integral lateral projections 16 thereon in lieu of the fingers 14—14 and 15—15. Any number of these projections may be provided as preferred, and each is either bendable, or of a springy characteristic, for gripping 95 the curtain rod to hold the body 12 in proper assembly with the rod. Obviously the body 12 illustrated may have artistic extensions 13 or not as preferred.

In some instances artistic extensions as 17, 100 similar to the extensions 13, may be provided directly upon the ends of the covering members 6—7, in which case the attaching means, such as the fingers 14—15, or 16—16, may be connected directly with the rear surface of 105 the covering member, as illustrated in Fig. 6, the separate end ornament members 9—10 being thus dispensed with.

In some instances also, if preferred, the 110 separately formed end ornament members 115

9—10 may be employed but the body portions 12 thereof being without attaching means. In this case the attaching means may be carried by separately formed body members as 5 18 intended to overlie the bodies 12, and the attaching means serving to bind all to the curtain rod as will be readily understood from an inspection of the drawings Fig. 7.

In Fig. 7 it is also suggested that if desired 10 separately formed body members 18, with attaching means thereon may be used for holding the central ornament members in position in the same manner as described with reference to the end ornament members.

15 The separately formed body members 18, with their connected attaching means, are desirable in that they enable the manufacture of these parts in quantities as a standard form of attaching member adapted to be employed 20 in connection with various designs and sizes of centre and end ornament members for holding said members to the curtain rod at any desired points.

In Fig. 7 it is also suggested that if desired 25 the bendable fingers 14—15 may be displaced by a spring clamp 19 made preferably of wire, and being of a general form as further illustrated in the drawings Figs. 8 and 9 wherein it will be seen that for each spring 30 clamp a single piece of wire is employed bent into inverted U-shape at its mid-portion as at 20 for engaging the rear surface of the curtain rod. This U-shaped portion is bowed forwardly as at 21 for fitting into the rear 35 open side of the curtain rod, as clearly seen in Fig. 9. The lower portions of the legs of the U spread downwardly and backwardly as at 22—22, and thence upwardly as at 23, the upper ends being bent forwardly to pass 40 over the top edge of the rod as at 24—24 and then downwardly to engage against the front surface of the rod as at 25—25. Although 45 this wire clip or clamp member may be used with or without a carrying member as 18 it is preferably connected to the rear surface of the member 18 so that said member constitutes an ornamental cover for the legs 25. If preferred however the legs 25 may 50 overlie the outer face of the member 18 and be attached thereto by solder or otherwise, or it may be wholly unattached and held merely by clamping pressure.

55 Here it may be noted that the spring clips or clamps 19 may be readily employed as attaching means in any instance above referred to with regard to the bendable fingers 14—15. In all cases the portions 23 and 24 of said clamp are intended to stand spaced away 60 from the curtain rod so as to provide for accommodation of the curtain material. The inclining portions 22—22 constitute a sort of flaring mouth to facilitate introduction of the clip downwardly over the curtain rod, and 65 the portion 21 is afforded ample resiliency to

enable it to easily but firmly grip rods of varying thicknesses.

The ornamental end bracket members 11 may be brackets in fact, or in appearance only, as preferred, and they may be used or not, at will. They are formed separately from all the other members hereinabove described and may be attached to or removed from the curtain rod at any time.

70 Ornamental end bracket members and their means of attachment are clearly illustrated in Figs. 10 to 12. Each consists of a body member G formed of a strip of metal bent into general U-shape having one end portion as 75 26 intended to be introduced and clamped between an adjacent end portion of one of the covering members 6—7 and the overlying end ornament member 9—10, and having its opposite end provided with an eye or opening 27 through which to loosely slidably receive 80 the adjacent end portion 2 of the curtain rod.

85 By this arrangement the body G is held substantially rigidly connected with the curtain rod and in a given position irrespective of the length of the portion 2.

90 Fixed to the member G is an ornamental cover piece H. The point of attachment of this cover with the body member is below the lower edge of the ornamental end member 9 as at A. Above this point the member H 95 extends forwardly and upwardly as at 28 along the forward face of the member 9, and below said point the member H is curved as at 29 backwardly and downwardly to stand adjacent to, or be fixed to, the wall or support 100 4. The portion 29 is bendable so as to be readily brought into desired relation with the wall 4, and may be provided adjacent its lower end with an aperture through which a nail or screw as 30 may be inserted and driven into 105 the wall 4 if desired.

110 It should be here noted, as illustrated, that when these end bracket members are employed it is preferable that the end ornament members 9—10 be so placed that one of the pairs of bendable fingers, as 14—14, thereof may be bent into retaining engagement around the adjacent covering member 6 only while the other pair, as 15, of said bendable fingers may be bent around both the member 6 and the curtain rod. This conveniently disposes the members 14—14 and 15—15 at opposite sides of the portion 26 of the body member G of the bracket and thereby provides for a firm clamping grip against 120 said portion 26.

125 The portion 26 of the body member of the bracket is preferably concaved to conform to the contour of the clamping surfaces by which it is engaged, thus to facilitate its definite placement and easy retention.

130 By placing the end ornament members 9—10 with only one pair of its fastening fingers as 15 engaging both the rod and the covering member 6 the ornament member is

thereby made to project further beyond the edge of the curtain. This is often desirable, and may obviously be resorted to at any time irrespective of whether an end bracket member is present or not.

The portion of the body G which extends upwardly and is apertured to receive the portion 2 of the curtain rod may in some cases be omitted in which instance the portion 26 is relied upon to support the ornamental part 28. With this arrangement the bracket and the end ornament members may be placed at any desired point along the length of the rod and member 6, irrespective of the relative position of the portion 2 of the rod. They may be placed so that the fingers 14 engage the member 6 and the fingers 15 both the member 6 and the rod as above mentioned, or they may be placed nearer to the center of the rod so that all of the fingers may engage about the member 6 and the rod, or, in instances where the member 6 projects sufficiently beyond the end of the rod and is suitably connected to the rod, they may be placed entirely beyond the end of the rod and be supported wholly by engagement of all of the fingers 14—15 with the member 6.

In some cases the centre ornament 18 may be relied upon to hold the covering members 6—7 in position without the use of fastening means at the outer ends of said covering members. If the end ornaments are separately formed these may be held in place merely by engagement of their fastening means about the covering members.

The curtain rods, as L, to which the elements comprising this invention are intended to be attached may be either extensible or not, though they are usually extensible, one section being slideable within the other in a well known manner as indicated at 31 in Fig. 2. The elements comprising the present invention make up an extensible device readily adjustable to accommodate itself to any adjustment of the parts of the curtain rod. That is to say: The portion of the covering and ornament members which overlap are longitudinally adjustable with respect to each other. They may be overlapped more or less as may be required to appropriately cover any length of rod, or to correspond with any adjustment of the parts of the curtain rod. Extra cover members 6—7, and extra centre ornament members 8, may be added to make up any length as may be required.

As many changes could be made in this construction without departing from the scope of the invention as defined in the following claims, it is intended that all matter contained in the above description, or shown in the accompanying drawings, shall be interpreted as illustrative only and not in a limiting sense.

Having thus described my invention, what

I claim as new and desire to secure by Letters Patent is:—

1. An ornamental cover for a curtain rod of the type indicated, said cover comprising a plurality of separately formed members arranged in juxtaposed relation to each other to collectively provide a cover for the rod, and means to hold said cover members connected with the rod. 70

2. An attachment for a curtain rod of the type indicated, said attachment comprising a plurality of separately formed members adapted to be arranged in juxtaposed relation to each other to collectively provide an ornamental cover for the rod, and attaching means carried by only a portion of said members adapted to engage the rod for holding all of said members connected with the rod. 75

3. An attachment for a curtain rod of the type indicated, said attachment comprising a plurality of separately formed members shaped to nest together to thereby collectively provide an ornamental cover for the rod, and parts carried by certain of said members whereby said members are adapted to serve for retaining the other members connected with the rod. 80

4. An ornamental cover for the face side of a curtain rod of the type indicated, said cover being adapted to extend along the length of the rod and being transversely concaved on its rear side to receive the rod in nested relation therein, and attaching means by which said cover may be held in position 100 upon the rod. 95

5. An ornamental cover for the face side of a curtain rod of the type indicated, said cover consisting of a plurality of separate members adapted to be arranged end to end along the length of the rod, said members being transversely concaved on their rear sides to receive the rod in nested relation therein, and attaching means by which said members may be held in position upon the 110 rod. 105

6. An ornamental cover for the face side of a curtain rod of the type indicated, said cover consisting of a plurality of separate members adapted to be arranged end to end along the length of the rod, said members being transversely concaved on their rear sides to receive the rod in nested relation therein, and means to hold said members in position including a separately formed attaching part adapted to engage adjacent ends of said members and the rod for holding said ends attached to the rod. 115 120

7. An ornamental cover for the face side of a curtain rod of the type indicated, said cover consisting of a plurality of separate members adapted to be arranged end to end along the length of the rod, said members being formed of a strip of sheet material bent transversely so as to be concaved upon 130

- their rear sides and convexed upon their front sides whereby to receive the rod in nested relation against their rear side and whereby adjacent end portions of said members 5 may be arranged in overlapping nested relation, and attaching means by which said members may be held in position upon the rod.
8. An ornamental cover for the face side 10 of a curtain rod of the type indicated, said cover consisting of a plurality of separate members adapted to be arranged end to end along the length of the rod, said members being formed of a strip of sheet material 15 bent transversely so as to be concaved upon their rear sides and convexed upon their front sides whereby to receive the rod in nested relation against their rear side and whereby adjacent end portions of said members may 20 be arranged in overlapping nested relation, a single attaching member adapted to engage about the adjacent ends of said overlapping members and to engage the rod for holding said ends connected with the rod, 25 and other attaching means by which to attach the remaining ends of said overlapping members to the rod.
9. An ornamental cover for a curtain rod 30 comprising opposite end ornament members, a centre ornament member, and a plurality of intermediate rod covering members, together with means whereby the ornament members are adapted to hold the intermediate members connected with the rod.
- 35 10. The combination with an extensible curtain rod of the type indicated, of an extensible cover therefor including a plurality of parts extensibly adjustable with respect to each other and means to hold said parts in 40 position of adjustment and connected with the rod.
11. An extensible cover for a curtain rod of the type indicated, said cover including a rod covering member and opposite end 45 ornament members formed separate from the rod covering member, said end ornament members having attaching means by which to attach themselves and the rod covering member with the rod.
- 50 12. An ornamental cover for a curtain rod of the type indicated, said cover including opposite end ornament members having attaching means by which to attach them to the rod, and rod covering means extending 55 between said ornament members having its opposite ends supported by engagement with said ornament members.
13. An ornamental cover for a curtain rod 60 comprising opposite end ornament members, a centre ornament member, and intermediate rod covering members, together with a plurality of attaching members adapted to engage the rod and said ornament members respectively to connect the ornament members 65 and the intermediate members with the rod.
14. An ornamental cover for a curtain rod, comprising opposite end ornament members, intermediate rod covering means, opposite end bracket members, and attaching means carried by the end ornament members adapted 70 to engage the rod for holding said ornament members said covering means and the end brackets connected with the rod.
15. A spring clip by which to hold a cover 75 connected with a curtain rod of the type indicated, said spring clip being made up from a length of springy wire, said wire being bent upon itself to provide a central portion for engaging the rear surface of the rod, the portions at opposite sides of the central portion extending downwardly and away from each other and thence upwardly spaced from the central portion, the upper ends being bent forwardly to pass over the upper edge of the rod and cover and being finally bent downwardly again to engage the front surface of the cover, and the whole being bent so that the portions of the wire for engaging the rear surface of the rod and the front surface of the cover serve to resiliently urge the rod 80 and cover toward each other.
16. An attachment for a curtain rod of the type indicated, said attachment comprising a plurality of separately formed members 85 adapted to be arranged in juxtaposed relation to each other for collectively providing an ornamental cover for the rod, certain of said members being cover members and others of said members being ornamental members, and means whereby the ornamental members may 90 be connected with the rod in engagement with the cover members to thereby support themselves and the cover members upon the rod.
17. An ornamental cover for a curtain rod, 95 where the curtain rod carries a curtain thereon by having the rod threaded through a hem of the curtain, said cover comprising an elongated member adapted to overlie the front side of the rod and to overlie the intervening portion of the curtain, said elongated member being concaved on its rear side to receive the rod and curtain in nested relation therein, and attaching means for interengaging between said elongated member and the rod 100 to hold the elongated member in covering 105 position.
18. An ornamental cover for a curtain rod, where the curtain rod carries a curtain thereon by having the rod threaded through a hem of the curtain, said cover comprising a plurality of cover members adapted to be placed end to end along the length of the rod, and a plurality of separate attaching members for engaging the cover members and having parts adapted to extend through the material of the curtain to a position embracing the rod to hold the cover members connected 110 with the rod.

In testimony whereof I affix my signature.

L. GESSFORD HANDY.

130
